UNITED STATES PATENT OFFICE.

PATRICK GORMLY AND LEWIS BRIDGE, OF PHILADELPHIA, PA.

STEAM-RADIATOR.

SPECIFICATION forming part of Letters Patent No. 270,053, dated January 2, 1853.

Application filed October 9, 1852. (No model.)

To all whom it may concern:

Be it known that we, PATRICK GORMLY and LEWIS BRIDGE, citizens of the United States, residing in Philadelphia, Pennsylvania, have 5 invented certain Improvements in Steam-Radiators, of which the following is a specification.

Our invention relates to a steam-radiator of the same character as that described in our 10 Patent No. 263,167, dated August 22, 1852, the principal difference between the present radiator and the patented one being in the method of constructing and connecting the inner and outer tubes, the object being to permit the 15 use of cast-iron tubes in place of the sheet-metal tubes described in the patent.

In the accompanying drawings, Figure 1 is a longitudinal section of a heater constructed in accordance with our invention and comprising 20 three radiators; Fig. 2, an enlarged section of one of the radiators; Fig. 3, a sectional plan on the line 1 2; Fig. 4, a longitudinal section of an indirect radiator constructed in accordance with our invention, and Fig. 5 an 25 end view of the heating-tubes and connections of said radiator.

Each radiator comprises an inner tube, A, and an outer tube, B, connected together at the ends, and inclosing an annular steam-space, *a*, each outer tube having branches *b*, so that a series of radiators may be connected 30 together by coupling-pipes *d* to form a heater of any desired size. On the inner tube, A, a short distance from each end of the same, are formed external ribs, *f*, and on the outer tube, B, at a corresponding distance from its ends, are formed internal ribs, *g*, the two sets of ribs coinciding when the tubes are fitted together, and thus forming at each end of the radiator 35 an annular chamber, which is filled with cement *h*, so as to effectually plug up the ends of the radiator and prevent the escape of steam.

The cement which we prefer to use is composed of cast-iron turnings moistened with sal-ammoniac; but any other cement which will 45 make a durable steam-tight joint may be used.

To increase the radiating surface of the outer tube and add strength to the same without unduly increasing the thickness, we corrugate said tube, as shown in Fig. 3, the corrugations, by preference, not extending beyond the ribs *g* in the direction of the length of the tube. The inner tube may also be corrugated, but this is not important.

In connecting a series of radiators to form 55 an indirect radiator, we prefer to adopt the plan shown in Figs. 4 and 5, the radiators being arranged within an outer casing in the inclined position shown, and connected to the supply and discharge pipes by long and short 60 branches.

In the radiator shown in our patent above alluded to the inner tube was flared at each end and riveted to the outer tube; but when the tubes are made of cast-iron this plan can- 65 not be resorted to; hence the substitution therefor of the annular plugs at the ends of the tubes. The outer tube may have but one branch instead of two; but in most cases two branches will be formed on said tube.

Instead of forming an external rib, *f*, on the tube A and an internal rib, *g*, on the tube B, a single rib formed on either tube and extending completely across the space *a* at each end may be employed. The use of two ribs is, 75 however, preferred.

We claim as our invention—

The combination of the inner tube, A, the outer tube, B, the rib or ribs closing the space between the tubes, and the cement filling *h*, as 80 specified.

In testimony whereof we have signed our names to this specification in the presence of two subscribing witnesses.

PATRICK GORMLY.
LEWIS BRIDGE.
